Primary Examiner — Marissa J Cash

Assistant Examiner — Rebecca Tsehay

(74) Attorney, Agent, or Firm — Akerman LLP; Peter A. Chiabotti

(57) **CLAIM**

The ornamental design for a lighter, as shown and described.

DESCRIPTION

FIG. 1 is a perspective view of the lighter showing my new design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

The portions shown in broken lines form no part of the claimed design.

1 Claim, 4 Drawing Sheets---
